PROPORTIONING DEVICE FOR FLUIDS

Robert J. Short, Cincinnati, Ohio, assignor to The Procter & Gamble Company, Cincinnati, Ohio, a corporation of Ohio

Application June 6, 1934, Serial No. 729,277

20 Claims. (Cl. 137—164)

This invention relates to a device for delivering two or more fluids simultaneously in definite proportions to each other, which can be varied at will.

5 The object of the invention is to provide a device of this character that will be smooth, positive and reliable in operation, adjustable to deliver different proportions as desired within reasonable limits, and which will stop all flow automatically if for any reason any one fluid falls below or exceeds the predetermined proportion limits.

10 A further object of the invention is to provide a device of the type described which is especially applicable to liquids and which has a high degree of accuracy and is practically devoid of errors due to slippage as compared with other proportioning devices of the rotary or piston pump design.

15 This application is related to my co-pending application, Serial Number 702,266, filed December 13, 1933.

20 In many industrial operations it is desirable to continuously mix two or more fluids in definite, and sometimes variable, proportions. The continuous proportioning of molten kettle soap and silicate of soda or sal soda solution in soap making, of crude vegetable oil and caustic soda solution for use in the continuous refining of vegetable oils, of petroleum oils and sulfuric acid, of a liquid and a gas, or of two or more gases, are examples of the use of this device; and many others might be mentioned.

25 Various devices have been proposed for accomplishing this object. Some give a pulsating flow instead of a smooth continuous flow; some of the devices cannot be closely controlled or cannot be readily adjusted to change from one proportion to another, and none, prior to my work, as far as I am aware, will automatically stop the flow if the flow of one of the fluids becomes interrupted or exceeds the desired limits. These difficulties are all overcome in my improved device. The present modification of my invention, while of general use, is especially applicable where the amount of secondary fluid is very small in proportion to the amount of primary fluid.

30 In the following description of my invention I have specifically referred to a device applicable to the proportioning of liquids. However, it is to be understood that I do not wish to limit myself to liquids only, but wish to include devices of similar design applicable to the proportioning of gases and liquids or of gases only. It is to

be considered within the scope of my invention to use rotatable members appropriate to the use of the proportioning device whether for liquids only, for gases and liquids, or for gases only, and by the term "fluids" I intend to include mobile substances of all of the various types to which I have herein referred.

35 My device, in its simplest form, as applied to two fluids, consists essentially in the use of a suitable differential, one of whose primary shafts 10 is caused to rotate by the flow of the primary liquid, the other of whose primary shafts is caused to rotate by the flow of the combined primary and secondary liquids, and whose secondary member actuates a valve or other suitable control device controlling the flow of one of the liquids so that it will always flow in the desired proportion to the primary liquid; and furthermore, an electrically operated valve or other suitable device so arranged as to stop the flow of 20 the primary liquid whenever the secondary liquid falls below or exceeds the desired limits. The stopping of the primary liquid will in any event automatically stop the entire device. Various modifications of this principle may be used; 25 and for the purpose of an exemplary disclosure, some of the preferred forms of the device and methods of applying same are more fully set forth herein. The accompanying drawings will make these parts and their interrelated action 30 clear.

40 Reference is made to these drawings wherein:

Figure 1 shows a plan view of one form of my device; 35

Figure 2 shows an elevational view thereof, and

Figure 3 shows another form of my device.

45 Referring to Figures 1 and 2, a pipe line, through which the primary liquid is supplied, is indicated 40 at 5. This liquid flows through a device 6, having a rotatable member which is caused to rotate in proportion to the flow of the liquid through it. This device may conveniently be a meter of known type having a counter 7 to indicate the quantity of liquid passing through the device in a given time. The shaft 8 of the rotatable member which is caused to extend from the casing of the meter is connected to one of the primary shafts 9 of the differential device 10. 50

55 11 indicates the pipe through which the primary liquid leaves the device 6 and flows through a suitable check valve 12 to pipe 13 where said primary liquid comes in contact with the secondary liquid. 14 indicates the pipe through

which the secondary liquid is delivered, preferably at a slightly higher pressure than the primary liquid, through a control valve 15, through a suitable check valve 16 and through a suitable 5 cock or valve 17 to pipe 13 which conducts both liquids to device 18. Device 18 may conveniently be a meter of the type having means 20 for adjusting the displacement volume and a connected scale 19. 21 indicates the shaft of the rotatable member of device 18, or an extension of same, which is adapted to drive, either directly or through suitable gear or chain and sprocket means, the secondary primary shaft 22 of the differential 10. A change-speed drive may also be employed, if required, to give the required speed on the shaft 22 of the differential, with reference to the speed of shaft 9, when it is desired to vary the proportion of the secondary liquid.

20 It is obvious that the rotation of shaft 21 will depend not only on the quantity of liquid mixture passing through the mechanism 18 but also on its displacement volume at a given rate of flow. Thus, if the flow of liquids is maintained 25 at a fixed rate and the displacement volume of said device is varied, the speed of shaft 21 will vary. If the change in displacement volume is accompanied by a corresponding decrease or increase in the volume of the mixture of liquids 30 passing through said device, the speed of the shaft 21 will remain unchanged. Since the rate of flow of the primary liquid will remain constant for any given set of conditions, any change in the displacement volume of the said device must 35 necessarily be compensated for by a corresponding change in the volume of the secondary liquid in order that the one primary shaft may revolve in the desired relation to the other primary shaft.

The particular type of differential mechanism 40 is not a limitation upon my invention. In my specific exemplary embodiment, the first primary shaft 9 carries a wide faced gear 23. The second primary shaft 22 of the differential is threaded as shown, the threads extending substantially 45 from end to end thereof inside the housing of the differential. Mounted on said threaded shaft 22 is a gear or secondary member 24 threaded internally to match the thread on shaft 22 so that its axis is concentric with the axis of the threaded shaft 22. The teeth in gear 24 engage with the teeth of gear 23. The hub of gear 24 is grooved and fitted with a collar provided with pins 25, so arranged that the end of a lever 40 must move laterally with the gear 24. The lever 40 is provided with a fulcrum 27 mounted upon an external support 28. The lever 40 is connected through a suitable linkage and lever 26 to the stem 29 of a valve 15 which is located in the pipe line carrying the secondary liquid. 30 indicates diagrammatically an electrical switch or contact means arranged to be moved by the lever 40, against abutments 31 and 32, so that an electrical contact will be made when the lever moves to an extreme position either to the right or to 55 the left. The closing of these contacts can be made, by known means, to operate means for stopping the flow of the liquids, and/or suitable signals. For this purpose I have shown the switch 30 connected by leads 33 and 34, in one of which a source of current 35 is inserted, to the solenoid 36 of a magnetically operated valve 37 in the outlet line 38 of the device. I have likewise shown a signaling means 39 connected in parallel with the solenoid. It will be noted that the valve 37 is in the line 38 beyond the point of entry of

the delivery line 14 for the secondary fluid. Any other known device for stopping the flow of the liquids may be used.

It will be clear from the foregoing that one means of adjusting the proportion of primary to secondary liquids is by varying the volume of displacement of the device 18. This method of adjustment, while it may throw the readings of the meter 18 off, has the advantage, within the limits of such displacement volume adjustment, of requiring no adjustment of the differential mechanism, nor the use of change speed devices.

In order to secure variations of proportions not within the limits of displacement adjustment of the secondary rotatable device 18, a sprocket 15 wheel, not shown, mounted on shaft 21 may be connected by a suitable chain to a sprocket wheel which may be attached to the second primary shaft 22 of the differential. The relative sizes of the sprocket wheels may be selected to give the 20 desired speed on shaft 22 of the differential with reference to the speed of shaft 9 when the two liquids are flowing in the predetermined proportion. Variable speed transmissions of any well known type or suitable gears may be used at these 25 points.

The principle of operation of the device of Figure 1 is as follows, assuming two liquids are to be mixed:

The flow of the primary liquid causes the rotating member or meter 6 to rotate in direct relation to the amount of liquid flowing, and through suitable connections causes primary shaft 9 of the differential to operate at a certain speed. The primary liquid then flows through pipe 11, joins pipe 13 through which the secondary liquid is flowing, and enters secondary device or meter 18. This mechanism, having an adjustable displacement, is adjusted so that its rotating shaft will cause the second primary shaft of the differential, through suitable connections, to operate at the correct speed with reference to the first primary shaft when and only when the total mixture of the primary and secondary liquids is flowing through said mechanism in the predetermined proportion. The construction of the differential shown is such that if these two primary shafts rotate at the required speed relation, the member 24 on the threaded shaft will maintain its position without lateral movement along the shaft 22; but if the primary shafts fail to rotate at the required speed relation, which can be caused only by a variation of the liquids from the predetermined proportion, then the member 24 will move in a lateral direction to the right or to the left along the threaded shaft, the direction depending on which shaft is moving faster. The lever attached to this secondary member 24 is thereby caused to move in the same direction as the member 24 and in combination with a suitable fulcrum will thus operate the stem of the balanced control valve to open or close same as required, thus increasing or decreasing the flow of the secondary liquid through the rotatable member 18 until the desired proportional rate of flow is again restored, whereupon the two primary shafts of the differential will again rotate at the proper speed relation, keeping the member 24 in a position of equilibrium. By suitably adjusting the length or position of the lever arms, a proper setting is obtainable so that the gear 24, in its lateral movement, disengages with the gear 23 at the maximum and minimum openings respectively of the valve 15. Thus any desired proportions within the limit of the valve are obtain- 75

able. The two liquids after passing through the apparatus may then discharge into a mixing device or elsewhere as desired. If the rate of flow of the primary liquid is changed by throttling at any point in the system, it is obvious that the device will automatically compensate for this through the differential by causing the rate of flow of the other liquid to change correspondingly, so as to maintain the same proportions of the two liquids. Likewise, any throttling of the discharge line carrying the mixed liquids will reduce the total flow without permitting the proportions of the two liquids to vary. If the flow of the secondary liquid is changed to an amount greater than can be compensated for by the operation of the differential and its control valve, the electrical device will then so operate as to stop the flow of both liquids until the cause of the trouble can be corrected.

It is, of course, possible so to design this type of differential that the two primary shafts, instead of rotating at identical speeds, will rotate at different speeds while maintaining the secondary member 24 in its proper laterally stationary position of equilibrium. This could be the case, for example, if the gear 23 were made with a different diameter and different number of teeth from the secondary gear 24. Such a variation, however, would be considered equivalent to the differential as described for all intents and purposes. It is also obvious that any other type of differential can be used instead of the one described, provided only that it has two driven primary and secondary members co-acting on a controlling member in such a way that the motion of the latter whether rotary or lateral, can be used to control the secondary liquid. Hence my invention is not limited to the use of the type of differential shown, but covers the use of any differential in substantially the manner described in connection with a suitable means of control. If the rotatable members 6 and 18 have any difficulty in driving the shafts of the differential without permitting slippage or leakage of liquid through same, "torque amplifiers" of known type may be installed to supply the power needed to drive the differential shafts; but this is not ordinarily necessary.

It is also to be understood that means of power transmission other than a lever or levers, as shown and described, may be used between the control member of the differential and the stem of the control valve or other controlled means. A rotary screw motion or a worm and gear type of transmission may be used, or any other of the many known mechanical means for accomplishing this object. My invention is not limited to the use of the lever, therefore, but is intended to cover any means of transmitting motion from the control member of the differential to the stem of the controlled valve or to the pump or to other controlled means in such a way as to affect the flow of the liquid.

The relative proportions of the two liquids can readily be changed, as hereinabove indicated, within limits of the apparatus by changing the displacement of the adjustable rotatable member 18. When necessary to make changes outside the limits of the displacement of device 18, the substitution of suitable sized gears or sprockets in the system will accomplish the result within any desired range. The relative sizes of rotatable members, or meters, pipe lines, and valves, will naturally be selected in accordance with the relative amounts of the different liquids to be

handled, so as to obtain suitable speeds of rotation of the shafts within the desired range for use in this device.

Three or more liquids may be mixed or delivered proportionately in the same way that two are mixed as shown in Figure 1 by adding another differential, another balanced control valve, and rotating device of adjustable displacement for each additional liquid, and by so arranging the apparatus that the primary liquid flows through the primary rotatable member then becomes mixed with the secondary liquid; the mixture of primary and secondary liquids flows through the secondary rotatable member then becomes mixed with a tertiary liquid; the mixture of primary, secondary, and tertiary liquids flows through the tertiary rotatable member, becomes mixed with the quaternary liquid and so on; and by arranging the apparatus so that the primary rotatable member operates the first primary shaft of the first differential, the secondary rotatable member operates the second primary shaft of the first differential and also the first primary shaft of the second differential, the tertiary rotatable member operates the second primary shaft of the second differential and also the first primary shaft of the third differential and so on, while the control member of each added differential controls a balanced valve in the pipe line supplying the corresponding additional liquid.

Figure 3 shows a somewhat different arrangement adaptable to the proportioning of three or more liquids, five liquid delivery lines being shown. 71 represents a gear driven by the primary rotatable member 70. Rotatable members 70', 70'', 70''', operate respectively threaded shafts 72', 72'', 72''', 72''''' on which are mounted internally threaded gears or secondary members 73', 73'', 73''', 73'''''. The teeth of the gear 71 mesh with the two broad faced gears 84 and 85. The teeth in the secondary members 73', 73'' and 73''', 73''''' mesh with the broad faced gears 84 and 85 respectively. The secondary members are attached to levers, 74', 74'', 74''', 74''''' respectively operating control valves 75', 75'', 75''', 75''''' in the pipe lines carrying the respective controlled liquids. Another variation of the above differential may be obtained by substituting a broad faced gear for gear 71 and by having secondary gears 73', 73'', 73''', 73''''' mesh directly therewith. The proper direction of rotation may be obtained with the use of suitable gears in connection with the respective shafts of the rotatable members. The operation of these arrangements is substantially the same as that of the corresponding arrangement previously described.

Each of the levers 74', 74'', 74''', 74''''' may bear switches 76', 76'', 76''', 76''''' connected in parallel to leads 77 and 78, which in turn are connected to the solenoid 79 of a cut-off valve 80 in the delivery line 81. There will be a suitable source of current at 82 for actuating the solenoid 79, and/or a signalling device 83 connected into the circuit. Any other known device for stopping the flow of liquids may be used.

It is obvious that when the proportions of the two or more liquids are permanently fixed, the use of an adjustable displacement rotatable device is unnecessary and in that case the secondary rotatable member can have a fixed displacement such that the passage of the correctly proportioned mixture of liquids through said secondary rotatable member will cause the one

primary shaft to revolve in the correct relation to the other primary shaft of the corresponding differential.

In order to prevent the continued flow of the primary liquid when the flow of the secondary liquid is interrupted for any reason, or when the required proportions cannot be maintained, a suitable electrical switch is provided. This may most conveniently be placed on the lever operating the balanced control valve, so as to operate as follows: If the flow of the secondary liquid stops or if its relative rate exceeds or falls below a desired point, the secondary member 24 of the differential will then automatically travel in a lateral direction along the shaft 22 far enough to operate the electric switch, which will then operate a suitable electrically controlled valve stopping the flow of the primary liquid, or the flow of both liquids; or it may be arranged to cut off the current supplying the motors which operate the pumps supplying the fluids. Either method, therefore, stops the apparatus entirely and it will not resume operation until the trouble is corrected.

This apparatus is easily constructed at moderate cost, is simple and positive in its action, gives a smooth flow of both liquids without pulsations, can be readily adjusted to any desired proportions of two or more liquids, and will not permit any flow if the desired proportions for any reason cannot be maintained.

Liquids of practically any kind or degree of viscosity can be handled satisfactorily in this device. Even liquids containing suspended matter forming a so-called sludge will operate satisfactorily, provided the said materials will flow like liquids.

As previously stated, this invention, although primarily designed for use on liquids, is also applicable to the proportioning of liquids and gases or of gases, provided, of course, the rotatable members are appropriately selected.

In the appended claims "primary" fluid refers to the "controlling" fluid and "secondary", "tertiary", etc., fluids refer to "controlled" fluids.

Having thus described my invention, what I claim as new and desire to secure by Letters Patent, is:—

1. A device for controlling the flow of secondary fluid in definite proportion to the flow of a primary fluid, comprising in combination a primary rotatable member in the line of flow of the primary fluid adapted to rotate in definite relation to the amount of fluid flowing, a secondary rotatable member in the line of flow of the mixture of the primary and secondary fluids, adapted to rotate in definite relation to the amount of combined fluids flowing, a control valve in the line of flow of the fluid to be controlled, a suitable differential, and power transmitting means between the different elements; so arranged that each of the said rotatable members causes one of the primary shafts of the differential to rotate, said primary shafts being caused to rotate at such a ratio of speed to each other as will hold the secondary member in a stationary position when the two fluids are flowing in the desired proportions but will cause movement in the secondary member of said differential when the said ratio is disturbed; said movement in the secondary member of the differential being of such nature as to actuate the said control valve so as to permit the fluid under control to flow again in the desired proportion.

2. A device for controlling the flow of a sec-

ondary fluid in any desired proportion to a primary fluid, comprising in combination a primary rotatable member in the line of flow of the primary fluid adapted to rotate in definite relation to the amount of fluid flowing, a secondary 5 rotatable member of adjustable displacement volume in the line of flow of the predetermined mixture of the primary and secondary fluids, adapted to rotate in definite proportion to the amount of combined fluids flowing, a control 10 valve in the line of flow of the fluid to be controlled, a suitable differential, and power transmitting means between the different elements; so arranged that each of the said rotatable members causes one of the primary shafts of 15 the differential to rotate, said primary shafts being caused to rotate at such a ratio of speed to each other as will hold the secondary member in a stationary position when the two fluids are flowing in the desired proportions but will 20 cause movement in the secondary member of said differential when the said ratio is disturbed; said movement in the secondary member of the differential being of such nature as to actuate the said control valve so as to permit the fluid 25 under control again to flow in the desired proportion; the desired proportion being adjustable by means of the adjustable secondary rotatable member.

3. A device for controlling the flow of fluids in 30 definite proportions to the flow of a primary fluid, comprising in combination a primary rotatable member in the line of flow of the primary fluid adapted to rotate in definite relation to the amount of fluid flowing, succeeding rotatable 35 members, one for each fluid being controlled, adapted to rotate in direct relation to the amount of combined fluid flowing, so arranged that, in succession, the controlling fluid is mixed with a controlled fluid then flows through the rotatable 40 member corresponding to that controlled fluid, a control valve in the line of each controlled fluid, suitable differentials, equal in number to the number of fluids to be controlled, and power transmitting means between the different elements; so 45 arranged that the primary shafts of each differential are caused to rotate by the rotatable members associated with the proportioning of the fluid controlled thereby, said primary shafts in each differential being caused to rotate at such a ratio 50 of speed to each other as will hold the secondary member of the differential in stationary position when its respective fluid is flowing in the desired proportion to the primary fluid, but will cause movement in the secondary member of the differ- 55 ential when the said ratio is disturbed; said movement in the secondary member of the differential being of such nature as to actuate the corresponding control valve so as to permit the fluid under its control to again flow in the de- 60 sired proportion to the primary fluid.

4. A device for controlling the flow of fluids in definite proportion to the flow of a primary fluid and for stopping the flow of the fluids when the flow of a controlled fluid falls below or exceeds 65 predetermined limits, comprising the device as described in claim 2 combined with a device comprising electrical switches equal in number to the number of controlled fluids actuated by the movement of the secondary member of the differential 70 and an electrically operated valve on a line carrying the mixture of proportioned fluids; so arranged that when the flow of a controlled fluid falls below or exceeds predetermined limits, the movement of the secondary member of the dif- 75

- ferential corresponding to that fluid will actuate the electrical switch causing an electric current to actuate a suitable device to stop the flow of the fluids.
5. A device for controlling the flow of fluids in definite proportion to the flow of a primary fluid and for stopping the flow of the fluids when the flow of a controlled fluid falls below or exceeds predetermined limits, comprising the device as described in claim 3 combined with a device comprising electrical switches equal in number to the number of controlled fluids, actuated by the movement of the secondary member of the differential and an electrically operated valve on a line carrying the mixture of proportioned fluids; so arranged that when the flow of a controlled fluid falls below or exceeds predetermined limits, the movement of the secondary member of the differential corresponding to that fluid will actuate the electrical switch causing an electric current to actuate a suitable device to stop the flow of the fluids.
6. A device for controlling the flow of fluids in definite proportions to the flow of a primary fluid, comprising in combination, a primary rotatable member in the line of flow of the primary fluid adapted to rotate in definite relation to the amount of fluid flowing, succeeding rotatable members of adjustable displacement volume, one for each fluid being controlled, adapted to rotate in direct relation to the amount of combined fluid flowing, so arranged that, in succession, the controlling fluid is mixed with a controlled fluid, then flows through the rotatable member corresponding to that controlled fluid, a control valve in the line of each controlled fluid, suitable differentials, equal in number to the number of fluids to be controlled, and power transmitting means between the different elements; so arranged that the primary shafts of each differential are caused to rotate by the rotatable members associated with the proportioning of the fluid controlled thereby, said primary shafts in each differential being caused to rotate at such ratio of speeds to each other as will hold the secondary member of the differential in a stationary position when the respective fluid is flowing in the desired proportion to the primary fluid but will cause movement in the secondary member of said differential when said ratio is disturbed; said movement of the secondary member of the differential being of such nature as to actuate the corresponding control valve so as to permit the fluid under its control to again flow in the desired proportion to the primary fluid, the desired proportions being adjustable by means of the adjustable rotatable members.
7. In a device for controlling the flow of a plurality of fluids in any desired proportion, means moved by the passage of a controlling fluid in accordance with its rate of flow, means moved by the flow of the mixture of controlling and controlled fluids in accordance with its rate of flow, means for controlling the rate of flow of said controlled fluids and motion transmitting means connecting said aforementioned means, said motion transmitting means being of a type to arrive at an equilibrium when the motion of said first two mentioned means is in the required proportion but to produce motion of said third mentioned means when said equilibrium is disturbed.
8. In a device for proportioning the flow of fluids, means for delivering a controlling fluid, motive means actuated by the flow of said fluid in said delivery means in proportion to said flow, means for delivering a controlled fluid, motive means actuated by the flow of a mixture of the
- said controlling and controlled fluids in said delivery in proportion to said flow, an equilibrium motion device having a plurality of primary driven parts and a secondary part adapted for movement upon the disturbance of a given relationship of motion of the primary driven parts, individual motion transmitting connections between said motive means and said primary parts, a valve in the delivery means of said controlled liquid and a connection between said valve and said secondary part.
9. In a device for proportioning the flow of fluids, means for delivering a controlling fluid, motive means actuated by the flow of said fluid in said delivery means in proportion to said flow, means for delivering a controlled fluid, motive means actuated by the flow of a mixture of the said controlling and controlled fluids in said delivery in proportion to said flow, an equilibrium motion device having a plurality of primary driven parts and a secondary part adapted for movement upon the disturbance of a given relationship of motion of the primary driven parts, individual motion transmitting connections between said motive means and said primary parts, a valve in the delivery means of said controlled fluid, a connection between said valve and said secondary part, valve means in said delivery means and means actuated by said secondary part for closing said valve means when said secondary part exceeds a given range of movement.
10. In a device for proportioning the flow of fluids, means for delivering a controlling fluid, motive means actuated by the flow of said fluid in said delivery means in proportion to said flow, means for delivering a mixture of the controlling and controlled fluids, adjustable motive means actuated by the flow of said mixture of controlling and controlled fluids in said delivery in proportion to said flow, an equilibrium motion device having a plurality of primary driven parts and a secondary part adapted for movement upon the disturbance of a given relationship of motion of the primary driven parts, individual motion transmitting connections between said motive means and said primary parts, a valve in the delivery means of said controlled fluid and a connection between said valve and said secondary part.
11. A device for controlling the flow of a plurality of fluids in definite proportion to a primary fluid, comprising in combination, a primary rotatable member in the line of flow of the primary fluid adapted to rotate in definite relation to the amount of fluid flowing, succeeding rotatable members, one for each fluid being controlled, adapted to rotate in direct relation to the amount of combined fluid flowing, so arranged that, in succession, the controlling fluid is mixed with a controlled fluid, then flows through a rotatable member corresponding to that controlled fluid, a control valve in the line of each controlled fluid, a suitable differential device having a plurality of primary driven parts, and a secondary part adapted for movement upon the disturbance of a given relationship of motion of the primary parts, and power transmitting means between the different elements so arranged that a common primary shaft is caused to rotate by the primary rotatable member, and that each of a plurality of other primary shafts, equal in number to the number of controlled fluids, is caused to rotate by one of the additional rotatable members, the primary shafts being caused to rotate at such a ratio of speed to each other as will hold the secondary part.

- members in a stationary position when their respective fluids are flowing in the desired proportion, but will cause movement in secondary members when the proportion of the corresponding controlled fluids to the controlling fluid is disturbed; said movement in the secondary member being of such nature as to actuate the respective control valve so as to permit the respective fluid to again flow in the desired proportion to the other fluids.
12. A process of proportioning fluids which comprises causing a primary fluid to flow through a conduit and to actuate moving means in accordance with its flow, adding thereafter to said primary fluid a secondary fluid, causing the combined fluids to actuate moving means in accordance with their combined flow, and causing said several moving means to interact upon a controlling means affecting the flow of said secondary fluid.
13. A process of proportioning fluids which comprises causing a primary fluid to flow through a conduit and to actuate moving means in accordance with its flow, adding thereafter to said primary fluid a secondary fluid, causing the combined fluids to actuate moving means in accordance with their combined flow, and causing said several moving means to interact upon a controlling means affecting the flow of said secondary fluid, providing cut-off means in the line of flow of said combined fluids and causing said controlling means at a predetermined position to actuate said cut-off means.
14. A process of proportioning fluids which comprises causing a primary fluid to flow through a conduit and to actuate moving means in accordance with its flow, adding thereafter to said primary fluid a secondary fluid, causing the combined fluids to actuate moving means in accordance with their combined flow, and causing said several moving means to interact upon a controlling means affecting the flow of said secondary fluid, and producing controlled variations in the flow of said fluids by producing changes in the displacement volume of said last mentioned moving means.
15. In a proportioned flow device, a conduit for a primary fluid, means in said conduit acting in accordance with the displacement volume to move a member in accordance with the rate of flow of said primary fluid, a conduit for a secondary fluid, said conduit joining said first conduit at a point beyond said displacement volume means, a second displacement volume means in said conduit beyond said juncture, and adapted to move a member in accordance with the rate of flow of said combined fluids and an interconnection between said moving members and a controlling member, and means whereby said controlling member may produce a variation in volume of said secondary fluid.
16. In a proportioned flow device, a conduit for a primary fluid, means in said conduit acting in accordance with the displacement volume to move a member in accordance with the rate of flow of said primary fluid, a conduit for a secondary fluid, said conduit joining said first conduit at a point beyond said displacement volume means, a second displacement volume means in said conduit beyond said juncture, and adapted to move a member in accordance with the rate of flow of said combined fluids and an interconnection between said moving members and a control member, and means whereby said control member may produce a variation in volume of said secondary fluid.
17. In a proportioned flow device, a conduit for a primary fluid, means in said conduit acting in accordance with the displacement volume to move a member in accordance with the rate of flow of said primary fluid, a conduit for a secondary liquid, said conduit joining said first conduit at a point beyond said displacement volume means, a second displacement volume means in said conduit beyond said juncture, and adapted to move a member in accordance with the rate of flow of said combined fluids and an interconnection between said moving members and a controlling member, and means whereby said controlling member may produce a variation in volume of said secondary fluid, the volume displacement of said second volume displacement means being adjustable to vary the proportion of said fluids without adjustment of said interconnection.
18. In a proportioned flow device a conduit for a primary liquid, means in said conduit acting in accordance with the displacement volume to move a member in accordance with the rate of flow of said primary liquid, a conduit for a secondary liquid, said conduit joining said first conduit at a point beyond said displacement volume means, a second displacement volume means in said conduit beyond said juncture and adapted to move a member in accordance with the rate of flow of said combined liquids, and an interconnection between said moving members and a controlling member, and means whereby said controlling member may produce a variation in volume of said secondary liquid.
19. In a proportioned flow device a conduit for a liquid, means in said conduit acting in accordance with the displacement volume to move a member in accordance with the rate of flow of said liquid, a conduit for a gas, said conduit joining said first conduit at a point beyond said displacement volume means, a second displacement volume means in said conduit beyond said juncture and adapted to move a member in accordance with the rate of flow of the combined liquid and gas, and an interconnection between said moving members and a controlling member and means whereby said controlling member may produce a variation in volume of said gas.
20. In a proportioned flow device a conduit for a primary gas, means in said conduit acting in accordance with the displacement volume to move a member in accordance with the rate of flow of said primary gas, a conduit for a secondary gas, said conduit joining said first conduit at a point beyond said displacement volume means, a second displacement volume means in said conduit beyond said juncture and adapted to move a member in accordance with the rate of flow of said combined gases, and an interconnection between said moving members and a control member, and means whereby said control member may produce a variation in volume of said secondary gas.
